(57) **CLAIM**

We claim the ornamental design for an electrical cable set, as shown and described.

DESCRIPTION

FIG. 1 is a perspective view of an electrical cable set, showing our new design;

FIG. 2 is a front elevational view thereof, the rear elevational view being a mirror image thereof;

FIG. 3 is a left-side elevational view thereof;

FIG. 4 is a right-side elevational view thereof;

FIG. 5 is a top plan view thereof; and,

FIG. 6 is a bottom plan view thereof.
